UNITED STATES PATENT OFFICE.

WILLIAM E. DRUMMOND, OF CHIEFLAND, FLORIDA, ASSIGNOR OF ONE-HALF TO
MORRIS W. COOPER, OF CHIEFLAND, FLORIDA.

SOCKET RATCHET WRENCH.

Application filed April 23, 1923. Serial No. 633,893.

To all whom it may concern:

Be it known that I, WILLIAM E. DRUMMOND, a citizen of the United States, residing in the city of Chiefland, county of Levy, 5 and State of Florida, have invented new and useful Improvements in Socket Ratchet Wrenches, of which the following is a specification, reference being had to the accompanying drawings.

10 This invention is in the way of a hand wrench, and may be more particularly described as a socket ratchet wrench for the general use of mechanics. The chief object of the invention is to provide a relatively simple, strong, durable and efficient wrench of the kind.

In the drawing—

Figure 1 is a side elevation of the wrench with the jaws contracted;

20 Figure 2 is a similar view with the jaws expanded;

Figure 3 is a detail of the hollow shank;

Figure 4 is a detail of the handle, a part being broken away to show the mounting 25 of the pawl;

Figure 5 is an end view of the shank;

Figure 6 is an end view of the two jaws;

Figure 7 is a side view of the two jaws;

30 Figure 8 is a view of the inner sides or faces of the two jaws;

Figure 9 is a detail of the jaw bar;

Figure 10 is a detail of the V-shaped jaw spring;

Figure 11 is a detail of the thumb-stud.

35 In carrying out this invention, a hollow shank 1 is provided, the same being chambered or recessed out longitudinally from the bit end 2 toward the handle end 3, with the rectangular jaw-cavity 4, which 40 has an elongated thumb-stud slot 5 opening outwardly at one side. Two tapered jaws 16 are provided, and adapted together to loosely fit up into the jaw cavity 4, the said jaws having angular nut recesses 45 6 in their ends and so adapted, together, to properly engage an ordinary square nut; and having also the medial spring recesses 7 and the jaw-bar notches 8 at their ends; all of the said recesses being formed on the 50 inner faces of the said jaws. A jaw-bar 9 is provided, having a shank portion 10 with the transverse thumb-stud hole 11 therein, and having an end cut away at the sides so as to form a draw head 12 55 adapted to be engaged by the two jaw bar

notches 8. A V-shaped spring 13 is formed and adapted to fit into the spring recesses 7, and serves normally to throw the jaws 16 asunder as they move out of the jaw cavity 4. A thumb-stud 14 is formed with 60 a stem 15 to tightly fit into the thumb-stud hole 11. The elements so aforescribed are assembled by fitting the end of the spring 13 into the recesses 7 with the apex of the spring set inwardly towards 65 the jaw bar notches 8. The draw head 12 of the jaw bar 9 is then placed within the notches 8 of the jaws, and these elements are all thrust within the jaw-cavity 4, the jaw bar 9 entering first. The stem 15 of 70 the thumb-stud 14 is then thrust through the slot 5 and tightly into the hole 11 of the jaw bar 9, whereby these elements are firmly locked together. If desired, in order to more firmly lock the elements together, a pin 23 may be passed through the shank 1 and between the wings of the 75 said V-shaped spring 13.

By moving the thumb-stud 14 back and forth in the slot 5, the jaws 16 are moved 80 outwardly and expanded to fit the particular nut being worked upon, or may be moved inwardly for a smaller sized nut. The opposite end of the shank 1 is reduced to the form of a circular ratchet 17, and a handle 18 is provided, the same having 85 a ratchet hole 19 at one end thereof, and a pawl 20 pivoted at 21 in a lateral pawl slot 22 and adapted to engage the ratchet 17, and so lock the handle 18 in fixed relation to the shank 1, on say the clock-wise turn of the handle 18, while permitting the handle to rotate freely over the rack when turned in opposite direction. The operation and use of this wrench is apparent from 90 the description given.

While I have herein described a certain specific manner and method of constructing and assembling the elements of my invention, it is understood that I may vary 100 from the same in minor details, not departing from the spirit of my invention, so as best to construct a practical device for the purpose intended, as defined in the appended claim.

I claim:

A wrench of the kind described, comprising a shank having at one end a longitudinal rectangular jaw-cavity, and an elongated thumb-stud slot at one side communicating 110

with the jaw-cavity, the opposite end of the shank being reduced to a circular ratchet; a pair of tapered jaws to fit into the jaw-cavity, the jaws being recessed on their inner contiguous faces to form nut-engaging recesses, spring-engaging recesses, and jaw bar head engaging notches; a V-shaped spring to fit into the said spring recesses of the jaws; a jaw bar having a draw head 10 adapted to be engaged by the said notches of the jaws and having a transverse thumb-stud hole in its shank portion; a thumb-stud having a stem adapted to pass through the thumb-stud slot of the shank and fit into

the thumb-stud hole of the jaw bar; a pin 15 passed through the shank between the wings of the V-shaped spring; a handle having a ratchet hole adapted to engage the ratchet end of the said shank, and having a lateral pawl slot communicating with the ratchet hole; and a pawl pivotally mounted within said pawl slot and adapted to engage the circular ratchet of the shank. 20

WILLIAM E. DRUMMOND.
